UNITED STATES PATENT OFFICE.

JOSEPH GOSSNER, OF NEW YORK, N. Y.

DESIGN FOR A COMBINED ASH TRAY, MATCH HOLDER, AND CIGAR CUTTER.

Application filed August 23, 1922. Serial No. 3,534. Term of patent 7 years.

To all whom it may concern:

Be it known that I, JOSEPH GOSSNER, a citizen of the United States, residing at New York, in the county of New York and State of New York, have invented a new, original, and ornamental Design for a Combined Ash Tray, Match Holder, and Cigar Cutter, of which the following is a specification, reference being had to the accompanying drawing, forming part thereof.

The figure is a perspective view of the combined ash-tray, match-holder and cigar-cutter showing my new design.

I claim:

The ornamental design for a combined ash-tray, match-holder and cigar-cutter as shown.

In testimony whereof I affix my signature.

JOSEPH GOSSNER.
